[57] CLAIM

The ornamental design for clamp for garment hangers or the like, as shown and described.

DESCRIPTION

FIG. 1 is a perspective view of a clamp for garment hangers or the like showing my new design;

FIG. 2 is an enlarged top plan view thereof, the portion of a garment hanger rod being shown in broken lines for illustrative purposes only;

FIG. 3 is an enlarged elevational view thereof, the portion of a garment hanger rod being shown in broken lines for illustrative purposes only, the rear being identical;

FIG. 4 is an enlarged right side elevational view thereof, both sides being identical;

FIG. 5 is an enlarged bottom plan view thereof.

FIG. 1.

FIG. 2.

FIG. 3.

FIG. 4.

FIG. 5.
